INDUSTRIAL VACUUM UNIT Billy D. Fyffe, 7423 E. 30th St.,
Tulsa, Okla. 74129

Filed July 21, 1975, Ser. No. 597,716

Term of patent 14 years

Int. Cl. D7—05; D15—05
U.S. Cl. D15—54FIG. 1 is an elevational view of an industrial vacuum unit showing my new design.

FIGS. 2 and 3 are left side and right side elevational views respectively.

FIGS. 4 and 5 are top elevational and bottom elevational views respectively.

I claim:

The ornamental design for an industrial vacuum unit, substantially as shown and described.
